UNITED STATES PATENT OFFICE.

HENRY S. BREWINGTON, OF BALTIMORE, MARYLAND.

SEALING DISK OR PACKING FOR BOTTLES OR OTHER VESSELS.

No. 800,261.

Specification of Letters Patent.

Patented Sept. 26, 1905.

Application filed May 12, 1905. Serial No. 260,184.

To all whom it may concern:

Be it known that I, HENRY S. BREWINGTON, a citizen of the United States, residing at Baltimore city, in the State of Maryland, have invented new and useful Improvements in Sealing Disks or Packing for Bottles or other Vessels, of which the following is a specification.

My invention relates to an improvement in sealing disks or packings for bottles or other closures where it is desirable to seal the mouth air and liquid tight and at the same time not affect the contents of the receptacle.

With the foregoing object in view my invention consists in the main in three distinct elements—namely, the outer metal cap; an inner lining of paraffin-paper or similar material, which affords a packing at the edge of the receptacle-mouth, and a disk or cylinder of cork, rubber, or similar material secured in any convenient way to the lining and adapted to enter and close the neck of the receptacle, thus preventing injury or impairment to its contents, while at the same time an inexpensive device is provided which may be constructed of scrap or other cheap stock.

My invention further consists in certain novel features of construction and combinations of parts, which will be hereinafter described, and pointed out in the claims.

In the accompanying drawings, Figure 1 is a vertical section of a bottle neck and cap of my improved form. Fig. 2 is a view in perspective of the improved bottle-stopper. Fig. 3 is a vertical section through the same. Figs. 4 and 5 are perspective views of the two disks separated. Fig. 6 shows them held together by adhesive material. Fig. 7 illustrates the invention applied to a fruit-jar or other large-mouthed receptacle, and Fig. 8 illustrates the inner disk elongated into a cylinder, adapted to extend farther into the bottle-neck.

Referring to Fig. 1, A represents the bottle-neck. 1 is an ordinary metal cap. A disk of paraffin-paper 2 is fitted and held frictionally therein and adapted to form a packing between the metal cap and end of the bottle. A smaller disk 3, of cork, rubber, or other elastic material, is secured by a staple 4, as shown in Figs. 1, 2, 3, 4, 7, and 8, or by adhesive material, as in Fig. 6, to the packing-disk 2, the purpose of this disk 3 being to extend into the bottle-neck and fit its walls and

to provide a material which is proof against the action of the contents of the receptacle. This packing-disk 2 may be made of any fibrous material and paraffined or not, as preferred. Ordinary cardboard would serve the purpose very satisfactorily. The disk 3 may be made of any material not easily acted upon by acids, and ordinary paper would suffice where the contents would not attack paper and it in consequence would not injure it.

In addition to the parts described a filler 5 of paraffin-paper or other material might be interposed between the disk 2 and the metal cap. 65

In Fig. 7, A' represents a jar or large-mouthed bottle or receptacle, and the cap is extended to form the threads 6 to screw upon the threads 7 of the can or jar.

In Fig. 8 the disk 3 is modified by making 70 it thicker in the form of a cylindrical block, as indicated at 3', whereby to extend farther into the mouth of the receptacle.

The cap is ordinarily spun around the bead 8 of the bottle-neck in the usual manner, as 75 shown in Fig. 1.

From the foregoing it will be seen that a very inexpensive device is formed which may be made entirely of scrap material, thus lessening the initial cost and at the same time 80 affording a practical article for the market. In removing the cap all parts come out together.

Slight additional changes might be resorted to in the form and arrangement of the several 85 parts described without departing from the spirit and scope of my invention, and hence I do not wish to limit myself to the exact construction herein set forth; but,

Having fully described my invention, what 90 I claim as new, and desire to secure by Letters Patent, is—

1. As an article of manufacture, a stopper for bottles and the like comprising a metal cap and a pair of disks of pliable material secured together and held wholly therein, one fitting the outer edge of the receptacle-mouth as a packing and the other the inner wall whereby a double seal is formed.

2. As an article of manufacture, a bottle-cap comprising a metallic cap, a disk held therein frictionally and adapted to engage and form a packing against the extreme outer edge of the bottle or receptacle mouth and a

smaller disk which enters and fits said mouth, its edge forming a sealing-contact against the inner wall of the receptacle-mouth while the adjacent surface of the other disk forms a 5 sealing-contact with the outer edge of said mouth, said disks secured together, wholly within the cap.

In testimony whereof I affix my signature in presence of two subscribing witnesses.

HENRY S. BREWINGTON.
